CLAIM

The ornamental design for a set of dice with letters and numbers, substantially as shown and described.

DESCRIPTION

FIG. 1 is a perspective view of an embodiment of a set of dice with letters and numbers incorporating the design; FIG. 2 is a front view of the set of dice with letters and numbers of FIG. 1; FIG. 3 is a rear view of the set of dice with letters and numbers of FIG. 1; FIG. 4 is a top view of the set of dice with letters and numbers of FIG. 1; FIG. 5 is a bottom view of the set of dice with letters and numbers of FIG. 1; FIG. 6 is a left side view of the set of dice with letters and numbers of FIG. 1; FIG. 7 is a right side view of the set of dice with letters and numbers of FIG. 1; FIG. 8 is a perspective view of another embodiment of the set of dice with letters and numbers incorporating the design; FIG. 9 is a front view of the set of dice with letters and numbers of FIG. 8; FIG. 10 is a rear view of the set of dice with letters and numbers of FIG. 8; FIG. 11 is a top view of the set of dice with letters and numbers of FIG. 8; FIG. 12 is a bottom view of the set of dice with letters and numbers of FIG. 8; FIG. 13 is a left side view of the set of dice with letters and numbers of FIG. 8; FIG. 14 is a right side view of the set of dice with letters and numbers of FIG. 8; FIG. 15 is a perspective view of another embodiment of the set of dice with letters and numbers incorporating the design; FIG. 16 is a front view of the set of dice with letters and numbers of FIG. 15; FIG. 17 is a rear view of the set of dice with letters and numbers of FIG. 15; FIG. 18 is a top view of the set of dice with letters and numbers of FIG. 15; FIG. 19 is a bottom view of the set of dice with letters and numbers of FIG. 15; FIG. 20 is a left side view of the set of dice with letters and numbers of FIG. 15; FIG. 21 is a right side view of the set of dice with letters and numbers of FIG. 15; FIG. 22 is a perspective view of another embodiment of the set of dice with letters and numbers incorporating the design; FIG. 23 is a front view of the set of dice with letters and numbers of FIG. 22; FIG. 24 is a rear view of the set of dice with letters and numbers of FIG. 22; FIG. 25 is a top view of the set of dice with letters and numbers of FIG. 22; FIG. 26 is a bottom view of the set of dice with letters and numbers of FIG. 22;

FIG. 27 is a left side view of the set of dice with letters and numbers of FIG. 22;

FIG. 28 is a right side view of the set of dice with letters and numbers of FIG. 22;

FIG. 29 is a perspective view of another embodiment of the set of dice with letters and numbers incorporating the design;

FIG. 30 is a front view of the set of dice with letters and numbers of FIG. 29;

FIG. 31 is a rear view of the set of dice with letters and numbers of FIG. 29;

FIG. 32 is a top view of the set of dice with letters and numbers of FIG. 29;

FIG. 33 is a bottom view of the set of dice with letters and numbers of FIG. 29;

FIG. 34 is a left side view of the set of dice with letters and numbers of FIG. 29;

FIG. 35 is a right side view of the set of dice with letters and numbers of FIG. 29;

FIG. 36 is a perspective view of another embodiment of the set of dice with letters and numbers incorporating the design;

FIG. 37 is a front view of the set of dice with letters and numbers of FIG. 36;

FIG. 38 is a rear view of the set of dice with letters and numbers of FIG. 36;

FIG. 39 is a top view of the set of dice with letters and numbers of FIG. 36;

FIG. 40 is a bottom view of the set of dice with letters and numbers of FIG. 36;

FIG. 41 is a left side view of the set of dice with letters and numbers of FIG. 36;

FIG. 42 is a right side view of the set of dice with letters and numbers of FIG. 36;

FIG. 43 is a perspective view of another embodiment of the set of dice with letters and numbers incorporating the design;

FIG. 44 is a front view of the set of dice with letters and numbers of FIG. 43;

FIG. 45 is a rear view of the set of dice with letters and numbers of FIG. 43;

FIG. 46 is a top view of the set of dice with letters and numbers of FIG. 43;

FIG. 47 is a bottom view of the set of dice with letters and numbers of FIG. 43;

FIG. 48 is a left side view of the set of dice with letters and numbers of FIG. 43;

FIG. 49 is a right side view of the set of dice with letters and numbers of FIG. 43;

FIG. 50 is a perspective view of another embodiment of the set of dice with letters and numbers incorporating the design;

FIG. 51 is a front view of the set of dice with letters and numbers of FIG. 50;

FIG. 52 is a rear view of the set of dice with letters and numbers of FIG. 50;

FIG. 51 is a front view of the set of dice with letters and numbers

FIG. 53 is a top view of the set of dice with letters and numbers of FIG. 50;

FIG. 54 is a bottom view of the set of dice with letters and numbers of FIG. 50;

FIG. 55 is a left side view of the set of dice with letters and numbers of FIG. 50;

FIG. 115 is a rear view of the set of dice with letters and numbers of FIG. 113;

FIG. 116 is a top view of the set of dice with letters and numbers of FIG. 113; FIG. 117 is a bottom view of the set of dice with letters and numbers of FIG. 113;

FIG. 118 is a left side view of the set of dice with letters and numbers of FIG. 113; and,

FIG. 119 is a right side view of the set of dice with letters and numbers of FIG. 113.

The broken lines showing portions of the set of dice with letters and numbers depict environment and form no part of the claim.
